UNITED STATES PATENT OFFICE

109,068

DESIGN FOR A COSMETIC CABINET

Preston W. Marshburn, Pelham, and Alexander Leydenfrost, New York, N. Y., assignors to Peggy Sage, Inc., New York, N. Y., a corporation of New York

Application November 20, 1937, Serial No. 73,054

Term of patent 14 years

To all whom it may concern:

Be it known that we, Preston W. Marshburn, a citizen of the United States, and Alexander Leydenfrost, a citizen of United States, residing at Pelham, in the county of Westchester and State of New York, and at New York city, in the county of Bronx and State of New York, respectively, have invented a new, original, and ornamental Design for a Cosmetic Cabinet, of which the following is a specification, reference being had to the accompanying drawings, forming part thereof.

In the drawings:—

Fig. 1 is a perspective view showing the front, side and top of a cosmetic cabinet illustrating our new design, with the cabinet door in closed position;

Fig. 2 is a similar view thereof but with the cabinet door in open position; and

Fig. 3 is a perspective view in closed position showing the top and other side thereof.

We claim:—

The ornamental design for a cosmetic cabinet as shown and described.

PRESTON W. MARSHBURN.
ALEXANDER LEYDENFROST.
